UNITED STATES PATENT OFFICE.

OLIVER P. SMITH, OF PORTLAND, OREGON.

BAG-FILLING APPARATUS.

Application filed March 1, 1921. Serial No. 443,926.

To all whom it may concern:

Be it known that I, OLIVER P. SMITH, a citizen of the United States, residing at Portland, in the county of Multnomah and State of Oregon, have invented certain new and useful Improvements in a Bag-Filling Apparatus, of which the following is a specification.

The invention relates to improvements in platforms for flour, feed and grain packing or sacking apparatus, and more particularly to an automatic regulator therefor.

In an apparatus of the class mentioned, a platform is generally provided for supporting the package or sack to be filled in position directly under the discharge spout or tube leading from a bin or hopper containing a supply of the flour, feed or grain, also, a mechanism is provided whereby the operator manually controls an operating mechanism for raising the platform after a package or sack is placed on the spout; manually actuates a device controlling the feeding of the material from the spout; and manually operates a lever to throw the feed mechanism to inoperative position, when the package or sack has been filled and the platform lowered.

A principal object of the present invention is therefore to eliminate certain of these manual controlling operations in such apparatus, and to render the same automatic, whereby to increase the efficiency of the apparatus, and, consequently, increase total daily output, as well as to render its operation less laborious on the operator of the same.

Briefly, the improved platform and automatic regulator therefor consists in providing the platform with a means whereby the same returns to raised or operative position automatically upon the removal of a filled package or sack therefrom, and in its downward movement a detent on the platform automatically operates a device for throwing the packing mechanism to inoperative position, thence leaving only the placing of the package or sack on the discharge spout, and the starting up of the packing mechanism as the only duties to be performed by the operator, in addition to taking off of the platform a filled package or sack. It is to be here noted that the time saved by the providing of automatic features of operation, as enumerated, allows for the sewing, or otherwise securing of the open end of a

filled package or sack, during which time another package or sack is being filled and lowered to position for removal from the platform.

With the foregoing and other objects in view, the invention resides in the present new and useful construction and arrangement of parts which will be hereinafter more fully described, set forth in the appended claim, and illustrated in the accompanying drawings, in which:

Figure 1 is a front elevation of a packing or filling apparatus and platform showing the invention applied thereto,

Fig. 2 is a side elevation thereof,

Fig. 3 is an enlarged detail showing an adjusting means for the brake band means for controlling the packing mechanism, and platform thereof,

Fig. 4 is an enlarged detail of the gearing of the packing mechanism,

Fig. 5 is a detail view of one of the actuating levers of the mechanism,

Fig. 6 is a fragmentary detail, in elevation, of the side of the platform opposite to that as shown in Fig. 2, and,

Fig. 7 is an enlarged detail of a means for securing the suspending chain of the platform to its winding shaft.

Referring to the drawings, wherein similar characters of reference designate corresponding parts in the several views thereof, the numeral 10 indicates the vertical uprights forming a frame together with spaced blocks 11, for supporting the lower ends of opposite pairs of the uprights 10, the intermediately rearwardly disposed cross pieces or blocks 12, the upper similar pieces or blocks 13, the transversely extending cross pieces or strips 14 disposed in the plane of the intermediate pieces or blocks 12, and the upper transversely extending cross pieces or strips 15 which lie in the plane of the pieces or blocks 13. Extending downwardly from its point of connection is a suitable bin or container (not shown) and diagonally of the upper part of the frame is a material feed tube 16 which connects at its lower end a discharge tube or spout 17, the latter being disposed between the front pair of uprights 10 of the frame. Mounted for vertical sliding movement between the uprights 10 of the frame is a platform 18, which has its forward edge extending outwardly of the uprights 10, whereby to be centered with respect to the

spout 17. The platform 18 is suspended in position by means of a pair of substantially triangular shaped supporting members 19 disposed at the opposite side edges thereof, the vertical sides of the members 19 rising from the rear side edge of the platform 18 with their inclined sides extending forwardly to points inwardly of the front edge of the same. The supporting elements 19 are suspended by means of chains 20 from a transversely extending shaft 21 which is suitably journalled on supporting blocks 22 extending between each pair of rear uprights 10 of the frame, the upper ends of the chains 20 having their end links engaged in eyes formed by the projecting looped ends of substantially inverted U-shaped elements 23, the legs of which elements 23 are passed through openings formed in the shaft 21 and headed as is shown in Fig. 7 of the drawings.

At one end of the shaft 21, immediately adjacent the outer faces of a pair of the uprights of the frame, is secured thereon a pulley 24 around which is formed a brake band 25, one end of the brake band 25 being secured, as at 26, to the outer face of one of the front uprights 10, and the other of its ends to an actuating lever arm 27, the latter having one end suitably pivoted, as at 28, to the frame support or upright, and its free end provided with an opening in which is engaged one end of an adjustable rod 29. This adjustable rod is in the form of separable sections 29 and 29', each having their adjacent ends threaded to receive a turn buckle 30. The sections 29' of the adjustable rod has its free end coupled through the medium of a coil spring 31, 40 to a hand lever 32, the latter being pivoted as at 33, to the front upright 10 at a point intermediate its end, the rear portion of the same projecting for a distance into the space between the front and rear uprights, 45 and its forward end to a distance beyond the front of the same and terminating in a hand grip 34 which projects outward beyond the plane of the vertical movement of the front edge of the platform, so as 50 to be accessible to the operator at all times to manipulate the brake band.

The opposite end of the shaft 21 has secured thereon a pulley or drum 35 to the face of which is secured one end of a flexible element or belt 36, which extends upwardly of the forward part of one side of the frame and is trained over a pulley 37 which is suitably journalled, as at 38, to the outer face of one of the uprights 10, the free 60 end of the flexible element of belt 36 extending for a distance below the plane of the pulley or drum 35, and having secured thereto a counterweight 39, the purpose of which construction and arrangement will be 65 hereinafter more fully described.

Suitably journalled in, as at 40 and 41, and vertically between the blocks or strips 14 and 15 at the upper front end of the frame is a shaft 42 which has its lower end projecting into the feed tube 16 in line with the vertical center of the discharge spout or tube 17, for the reception of suitable packing element or auger (not shown). A beveled gear 43, preferably of friction gear type as shown, is keyed on the shaft 42 between the journals 40 and 41, and is arranged to contact with a similar but smaller friction gear 44 carried on a power shaft 45, the latter projecting at one side of the frame and having a pulley 46 at or adjacent its outer end over which is trained a belt 47 leading to a suitable force of power (not shown). The end of the shaft 45 immediately adjacent the gear 44 is carried in a journal 48 which is, in turn, carried on a vertical movable shaft or rod 49, the latter being operable to raise and lower the shaft 45 and journal 48 sufficient to move the gear 44 into and out of contact with the gear 43. This mechanism is interconnected for operation with the brake band mechanism, and is properly manipulated for its sequence of operation from the hand lever 32, through the medium of an actuating lever 50 which is formed at its inner end with a forked yoke 51 (see Fig. 5) for pivotally connecting the rod 49, as at 52, and, in turn, the lever 50 is pivoted, as at 53, to the upper face of the cross bar 14, the outer end of the same projected to one side of the frame and having its free end connected to the hand lever 32 through the medium of a connecting rod 54.

In the operation of the mechanism constructed and arranged as hereinbefore described, and with the platform 18 in its normally raised position, the operator draws a sack or other similar container over the mouth of the spout 17 and, with power applied through the belt 47 to the pulley 46 and the shaft 45, grasps the hand grip 34 of the lever 32 and pushes the same downward, so as to raise the gear 44 into contact with the gear 43, this starts the packing mechanism on the shaft 42 within the spout 17 to feed flour, feed, grain or the like from the feed tube 16 into the bag or sack. This downward movement of the lever 32 tightens the brake band on the pulley 24, and the platform 18 is lowered, 120 by the unwinding of the chain 20 from the shaft 21 under the packing action of the material within the bag or sack, and against the frictional tension of the brake band, the latter being resiliently tensioned by 125 means of the coil spring 31 so as to allow a slow turning movement of the pulley 24 within the same. During the down-movement of the platform 18, the belt 36 is wound on the pulley or drum 35, and the counter- 130

weight 39 is raised, and when the platform 18 reaches the lower limit of its movement and the filled bag or sack is removed therefrom, the counterweight immediately acts 5 to unwind the belt 36 from the pulley or drum 35, and turns the shaft 21 in a reversed direction for the rewinding of the chain 20 thereon, and thus bringing the platform back to normally raised position.

10 When the platform 18 reaches its lower position, a detent 55 carried by one of the supports 19 engages the inner projecting end of the lever 32 and actuates the same to normal position, which causes a lowering of 15 the gear 44 from meshing with the gear 43 to cut off power from the packing mechanism, and a loosening up of the brake band 25 on its pulley 24. The mechanism is now ready for a repeat operation, and during 20 the interval of the filling or packing operation of another bag or sack, and the return of the platform from lowest to highest position, the operator is permitted time to rest from his labors, or to close and secure the 25 mouth of the bag or sack already filled during the previous operation of the mechanism.

It is to be understood that while the invention has been described in very specific

terms, various changes in details of construction and arrangement of the parts of the same may be resorted to without departing from the spirit and scope thereof.

Having thus fully described the invention, what is claimed, is:—

An apparatus for the purpose set forth comprising a frame, a load carrying platform, means for elevating and lowering said platform, a counter-balanced device and a brake band mechanism acting on said means for respectively moving the platform upwardly and for retarding the downward movement of the platform, a lever arm pivoted to said frame, a resilient element having one end connected with said lever arm, an adjustable sectional connection connected with said brake band mechanism and with the other end of said resilient element and in connection therewith and said lever arm providing means for shifting said brake band mechanism to active position, and means operated from said lever arm for connecting and disconnecting said drive from a power source.

In testimony whereof I affix my signature hereto.

OLIVER P. SMITH.
